US0D1037255S

(12) **United States Design Patent** (10) **Patent No.:** **US D1,037,255 S**
(45) **Date of Patent:** **** Jul. 30, 2024**

(54) **USB CABLE**

(71) Applicant: **Tengfei Liu**, Kaifeng (CN)

(72) Inventor: **Tengfei Liu**, Kaifeng (CN)

(**) Term: **15 Years**

(21) Appl. No.: **29/942,963**

(22) Filed: **May 19, 2024**

(51) LOC (14) Cl. **14-02**

(52) U.S. Cl.

USPC **D14/433**

Assistant Examiner — Russell Carnell Smith, Jr.

(57) **CLAIM**

The ornamental design for a USB cable, as shown and described.

DESCRIPTION

FIG. 1 is a perspective view of an USB cable showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the USB cable in an alternate state of use.
The broken lines depict portions of the USB cable and form no part of the claimed design.

1 Claim, 8 Drawing Sheets
